JEWELRY FINDING

Julio J. Marsella, Providence, R. I.

Application March 16, 1955, Serial No. 35,071

Term of patent 14 years

(Cl. D45—19)

Fig. 1

Fig. 2

Fig. 3

Fig. 4

In the drawing,

Fig. 1 is a plan view of a jewelry finding showing my new design;

Fig. 2 is a side view thereof;

Fig. 3 is a rear view thereof; and

Fig. 4 is an enlarged section on the line 4—4 of Fig. 1. I claim:

The ornamental design for a jewelry finding, as shown.
